(57) **CLAIM**

The ornamental design for a siding panel as shown and described.

DESCRIPTION

FIG. 1 is a front perspective view of a siding panel.

FIG. 2 is a front elevation view of the siding panel of FIG. 1.

FIG. 3 is a side elevation view of the siding panel of FIG. 1.

FIG. 4 is a bottom perspective view of the siding panel of FIG. 1.

FIG. 5 is a top plan view of the siding panel of FIG. 1; and, FIG. 6 is a bottom plan view of the siding panel of FIG. 1. The broken lines shown in the drawings depict portions of the article that form no part of the claimed design.

The siding panel includes a symbolic break along its length. The break lines and the areas between the break lines forms no part of the claimed design.

1 Claim, 5 Drawing Sheets
